BEVERAGE DISPENSER, OR SIMILAR ARTICLE

Richard T. Cornelius, Minneapolis, and James Robert Reichow, Edina, Minn., assignors to The Cornelius Company, Anoka, Minn., a corporation of Minnesota

Filed Jan. 3, 1964, Ser. No. 78,070

Term of patent 14 years

(Cl. D2—3)

The dominant features of our design reside in the lamp portion shown in full lines. The shading of the drawing views indicates color contrast.

We claim:

The ornamental design for a beverage dispenser, or similar article, substantially as shown and described.
